UNITED STATES PATENT OFFICE.

ALONZO T. ADAMS, OF EAST MOLINE, ILLINOIS, ASSIGNOR TO MARSEILLES COMPANY,
OF EAST MOLINE, ILLINOIS, A CORPORATION OF ILLINOIS.

ELEVATOR.

1,114,424.

Specification of Letters Patent.

Patented Oct. 20, 1914.

Original application filed March 25, 1909, Serial No. 485,640. Divided and this application filed August 15, 1913. Serial No. 784,858.

To all whom it may concern:

Be it known that I, ALONZO T. ADAMS, a citizen of the United States, residing at East Moline, in the county of Rock Island and State of Illinois, have invented certain new and useful Improvements in Elevators, of which the following is a specification, reference being had therein to the accompanying drawing.

10 My invention relates to that type of elevators having an adjustable hollow mast used to elevate grain and other materials to bins, cars and other places, and it is especially directed to certain new and useful 15 organizations and arrangements of parts for supporting and raising and lowering the mast.

The invention consists in the matters hereinafter disclosed and then pointed out in the 20 appended claims.

In the accompanying drawings illustrating a practical embodiment of my present invention and in which the same reference numerals indicate corresponding parts in the 25 several views,

Figure 1 is a side view of an elevator exemplifying my invention arranged for use and with the receiving hopper in position to receive the material to be dumped from the 30 wagon, the upper end of the elevator being broken away; Fig. 2 is a detail plan view of the rear portion of the base or body with the winding-drum and associated parts for the trolley-arm cable; Fig. 3 is a sectional view 35 on the line 3—3 of Fig. 5; Fig. 4 is a detail view of the elevator and its trolley-arm in elevation, and Fig. 5 is a side view of certain parts shown in Fig. 1 but with the elevator swung down to its inoperative position.

40 The elevator may be either stationary and permanently located or it may be portable, and for this latter purpose a suitable base or body may be employed, consisting in the 45 present instance of parallel beams 19 suitably connected and spaced apart, and preferably is in the form of a truck supported upon front and rear wheels as clearly shown in Figs. 1 and 5.

50 The elevator comprises a tubular hollow mast 20 preferably made of a suitable diameter of well-tubing, and a conveyer comprising an endless series of correspondingly shaped buckets or flights 21 having a slid-

ing fit in the bore of the mast and connected 55 by a suitably driven chain 22. In the present exemplification the flights are notched or recessed to approximately their centers and the chain rests in these notches being suitably connected to each flight in 60 such manner as to hold the same approximately at right angles to the chain, and the return run travels above or upon the upper side of the mast so that the notches in the flights face or open downwardly and co- 65 operate with a guide or track 23 secured on or above the upper side of the mast.

The mast is so pivoted upon the base so as to rest when out of use in horizontal position as shown in Fig. 5 and to be set at an 70 incline thereto when in use. To accomplish this result I mount the mast near its lower or receiving end in an upright swinging frame 24 pivotally mounted between two of the beams 19 near the front end of the base so as to 75 swing forwardly and downwardly and preferably concave at its upper end to receive the mast. The base is provided at its rear end with an upright bracket forming a seat 25 in line with the swinging frame and 80 adapted to receive and support the rear or free end of the mast when the latter is lowered as shown in Fig. 5. When the rear end of the mast is raised the frame 24 swings forwardly and downwardly and carries the 85 mast bodily outward and forward so that it clears the front axle of the wagon and its front end is beyond the forward end of the base or truck and can swing down to approximately the level of the ground, and 90 when it swings back to horizontal position it is drawn or carried bodily rearward so that its lower or front end is drawn upwardly and in toward the base or truck and will not interfere with horses hitched to a 95 suitable tongue, etc., attached at 26 to the truck to transport the elevator from place to place.

To raise and lower the mast I provide a trolley-arm 27 pivotally mounted on the 100 base and carrying a trolley-wheel 28 at its free end. The trolley-arm underlies the mast and is pivoted on the base near the rear end, and it consists of a pair of angle bars pivoted respectively to two of the 105 beams 19 approximately over the rear axle of the truck and spaced apart sufficiently to overlie the seat 25 when the arm is lowered;

the bars are suitably connected by cross braces 29 to form a rigid structure and carry the revoluble trolley-wheel between their free ends, the wheel preferably having a concave face to fit the curve of the mast. The arm is also provided near its free end with a sheave 30 around which a rope or cable 31 passes; one end of the rope is attached at the upper end of an upright 32 fixed on one side of the base to one of the beams 19 from whence it passes over the sheave 30 and thence over another sheave 33 at the top of a corresponding upright 34 on another beam 19 on the other side of the base, thence down over a third sheave 35 mounted centrally of the base near the bottom of the uprights and in line with a winding-drum 36 mounted in bearings on the base near the pivotal point of the trolley-arm. The uprights 32 and 34 are spaced apart sufficiently to allow the mast to pass between them when it is lowered.

The drum may be operated by any suitable means, and for this purpose I employ in the present exemplification a crank handle 37 rigid with a small sprocket wheel 38 mounted upon the outer face of the base and which transmits motion by a sprocket chain 39 to a larger sprocket wheel 40 on the drum. The wheel 38 is provided with a holding dog 41. These parts are clearly shown in Figs. 1 and 5. The uprights 32 and 34 are suitably braced as shown at 42. With this arrangement when the mast is in horizontal position resting in its seat 25 and it is desired to tilt it more or less, the operator winds the cable on its drum 36 and the pull of the cable being at an angle to the trolley-arm as seen in Fig. 5 causes the same to turn on its pivot to raise its outer or free end which in turn lifts the outer or free end of the mast and swings the frame 24 forward and downward to the position shown in Fig. 1. By this arrangement the receiving end of the mast is swung down to approximately the level of the ground or floor on which the machine stands so that the top of its angular boot 48 stands approximately horizontal and the usual associated receiving-hopper 69 is below the level of the end-gate of a wagon and is in position to receive the contents of the wagon when it is dumped therein. The mast may be raised to its extreme or any intermediate position and the dog 41 will hold it in position. When it is desired to lower the mast partially or wholly the dog is released and the operator allows the mast to slowly swing down by gravity, the trolley-arm of course being cammed down by and along the mast.

The upper end of the mast carries a bearing for a suitable sprocket wheel over which the conveyer-chain runs, and its lower end is provided with the boot angular 48 which affords bearings for a drive shaft 49 having

a sprocket in the boot for driving the conveyer flights, the shaft 49 extending through the boot and being suitably connected with the tumbling rod (not shown) of a horse power or driven from the head-shaft or from a suitable motor mounted on the base. The boot forms a support for one end of a receiving hopper 69 which is mounted so as to be swung out of the path of the loaded wagon to allow the latter to move to position to dump its contents and then swung to place in the rear of the wagon to receive the material dumped therefrom. The receiving hopper is preferably provided with a conveyer driven from shaft 49, and its discharge forms a detachable and horizontally adjustable connection with the top of the boot.

This application is a division of my earlier filed application bearing Serial Number 85 485,640, filed March 25, 1909.

I claim:

1. In a device such as described, a base, a tubular mast mounted in a downwardly swinging frame pivoted near one end of the base, a trolley-arm mounted near the other end of the base below the mast and bearing at its free end upon the underside of the mast to raise the same, means to swing the trolley-arm upon the base, and a conveyer having its carrying run in the mast and its return run on the upper side thereof.
2. In a device such as described, a base, a tubular mast mounted in a downwardly swinging frame pivoted near one end of the base and having an angular boot, a conveyer having its carrying run in the boot and mast and its return run on the upper face of the mast, a trolley-arm pivotally mounted near the other end of the base below the mast and having a roller at its free end bearing upon the underside of the mast to raise the same, and means to move the trolley-arm upon its pivot.
3. In a device such as described, a base, a tubular mast mounted in an upright downwardly swinging frame pivoted near one end of the base, a seat near the other end of the base and in alinement with the frame, a trolley-arm pivotally mounted on the base below the mast and between the frame and seat and extending beyond the latter at its free end, a roller in the free end of the trolley-arm bearing on the underside of the mast to raise it, means to swing the trolley-arm on its pivot, and a conveyer having its carrying run in the mast and its return run on the upper face thereof.

4. In a device such as described, a base, a tubular mast mounted in a downwardly swinging frame pivoted near one end of the base, a trolley-arm pivotally mounted near the other end of the base and bearing at its free end upon the mast to raise the same, a sheave on the trolley-arm, a pair of up-

rights on the base on opposite sides of the mast, a cable running through the sheave and fixed at one end to one of the uprights above the pivot of the arm, a sheave on the 5 upper end of the other upright through which the cable runs, and a winding-drum mounted on the frame to receive the free end of the cable to raise and lower the arm.

5. In a device such as described, a base, 10 a tubular mast mounted in a downwardly swinging frame pivoted near one end of the base, a conveyer having its carrying run in the mast and its return run on the upper face thereof, a trolley-arm pivotally mounted 15 on the base and having a roller at its free end bearing upon the mast to raise the same, a sheave on the trolley-arm, a cable running through the sheave and drawing toward a point above the pivot of the arm, and winding-drum mounted on the frame to receive 20 the cable to raise and lower the arm.

6. In a device such as described, a base, 25 a tubular mast mounted in a downwardly swinging frame pivoted near one end of the base, a conveyer having its carrying run in the mast and its return run on the upper face thereof, a trolley-arm pivotally mounted near the other end of the base and having a roller at its free end bearing upon the 30 mast to raise the same, a sheave on the trolley-arm, a pair of uprights on the base on

opposite sides of the mast, a cable running through the sheave and fixed at one end to one of the uprights above the pivot of the arm, a sheave on the upper end of the other 35 upright through which the cable runs and a winding-drum mounted on the frame to receive the free end of the cable to raise and lower the arm.

7. In a device such as described, a base, 40 a tubular mast mounted in an upright downwardly swinging frame pivoted at or near one end of the base, a seat at or near the other end of the base and in alinement with the frame, a trolley-arm pivotally mounted 45 on the base between the frame and seat and extending beyond the latter at its free end, a roller in the free end of the trolley-arm bearing on the mast to raise it, a sheave on the arm, a pair of uprights on the base or 50 opposite sides of the base between the frame and arm, a sheave on the upper end of one of the uprights, a cable connected to the upper end of the other upright and passing over the sheaves, and a winding-drum for 55 the cable on the base.

In testimony whereof I affix my signature in presence of two witnesses.

ALONZO T. ADAMS.
